FRANK C. ANDERSON, OF CINCINNATI, OHIO.

SWITCH-RAIL GUARD.

1,414,767.

Specification of Letters Patent. Patented May 2, 1922.

Application filed November 12, 1921. Serial No. 514,773.

To all whom it may concern:

Be it known that I, FRANK C. ANDERSON, a citizen of the United States, residing at Cincinnati, in the county of Hamilton and State 5 of Ohio, have invented certain new and useful Improvements in Switch-Rail Guards, of which the following is a specification.

My invention relates to switches, and its object is to avoid derailments caused by objects wedged between diverging rails of a switch when dragged by passing trains; and especially to accomplish this purpose with relation to point-rail switches thus having objects, such as chains, headed rods or bolts, 10 accidentally dropped and dragged by the trains, forced between the outside siding or turn-out rail and the adjacent point-rail in trailing direction, forcing this point-rail open sufficiently to admit the flanges of a 15 train passing in the opposite or facing direction and thus causing derailment of this subsequent train. A further object is to afford a positive movement of the guarding element into and out of guarding position, 20 for use of the main line and the siding or turn-out; and it also is an object to effect this movement automatically incident to the throwing of the switch. Other objects will appear in the course of the ensuing description. 25

I attain these objects by the device illustrated, for example, in the accompanying drawing, in which—

Figure 1 is a general plan view of parts 35 of a point-rail switch with my invention applied thereto;

Fig. 2 is a sectional side elevation of the same, part of the point-rail being omitted to reveal the guard element and its supporting 40 means;

Fig. 3 is an enlarged plan view of the guard element and adjacent parts, corresponding to Fig. 1;

Fig. 4 is a similarly enlarged side elevation corresponding to Fig. 2, dotted lines indicating a different position of the parts;

Fig. 5 is a vertical cross-section on the planes of the broken line 5—5 of Fig. 4;

Fig. 6 is a detail bottom plan view of the 50 guard element; and

Fig. 7 is a detail perspective view of one of the idler arms.

Part of the usual point-rail switch is shown, the siding or turn-out rail 1 being 55 continuous with the main-line rail extending to the switch in facing direction and the

main-line point-rail 2 being against the rail 1 when the switch is closed for main-line use as shown. The other side of the track is not shown, but the brace-rods 3 and 4 are seen, 60 fixed to the point-rail 2, and it will be understood that these are fixed to the opposite point-rail not shown, causing the two rails to move in unison when the switch is thrown. The rod 3 nearest the point of the rail 2 extends out and has connected to its outer end the connecting-rod 5, as usual, which will be understood to be connected to the operating mechanism of a suitable switch-stand of any kind, not shown. The two cross-ties 6 and 65 7, flanking the brace-rod 3 and connecting-rod 5, also extend out past the other cross-ties 8, for supporting the switch-stand, as usual. As is well understood, the siding continuous rail 1 is spiked in fixed condition on the ties 6, 7 and 8, and the point-rail, articulated to the continuation of the main-line rail beyond the switch to the left, not shown, is slidably supported on plates 9 fixed to the ties 6, 7 70 and 8. 75

In the preferred construction of my invention as shown, a plate 10 is provided, of cross-section to fit snugly against one side, preferably the inner side, of the siding-rail 1, under the ball or head 11 and over the base 85 1, or flange 12 and against the web 13 of this rail (Fig. 5.) This plate is of suitable length, receiving studs 14 through openings in the plate near opposite ends thereof, at such a height that these studs 14 will extend 90 out through registering openings bored in the web 13 of the rail 1, at about midway of the height of the web. Nuts 15 are screwed onto the outer ends of the studs 14, clamping the plate 10 and rail-web 13 together between these nuts and shoulders 16 formed on the studs 14 and coming against the exposed side of the plate 10, past which the studs 14 extend with enlarged diameter, toward the point-rail 2, ending in heads 17. The shaft 100 18 extends through an opening about midway of the length of the plate 10 and through a registering opening in the rail-web 13; which plate and web thus form one bearing for the shaft 18. The shaft preferably is 105 located somewhat below the studs 14, to avoid placing all of the holes in alignment in the rail-web 13 and thus unduly weakening the rail 1. The plate 10 reinforces this rail where it thus is bored; and this plate affords 110 a templet for the correct location of the holes in this rail.

100

105

110

The guard element 19 is an elongated body, preferably of malleable cast iron, tapering to conform approximately with the adjacent sides of the head 11 of the siding-rail 1 and the head 20 of the main-line point-rail 2, but be spaced an easy working distance therefrom at its opposite sides, at such a location along the rails that its wider end sufficiently fills a space between the diverging rails which is too wide to catch the largest object liable to be dragged between these rails by a passing train as before mentioned; and this element 19 is made long enough to fill the space between the rails sufficiently, for such a distance that, at its narrower end, the space will be too narrow to catch the smallest object thus dragged and liable, if caught, to wedge open the point-rail 2. Thus proportioned and located, the element 19 has its top substantially flat and smooth and designed to lie approximately in the plane of the tops of the rails 1 and 2; rather below than above the tops, since if above, it will receive the pressure of the train wheels. At its wider end, this element preferably has a pair of arms 21, between which a roller 22 is journaled on a transverse pin 23 in the arms. This roller 22 preferably has its face considerably crowned, or beveled from its middle both ways, and is journaled low enough for its uppermost part to escape the pressure of the train wheels, yet high enough to be engaged by any object dragged as before mentioned, and deflect the object to one side or the other, over the adjacent rail 1 or 2, or else up onto the top of the element 19, instead of allowing such object to catch under the end of the element and tear up the guard.

The operating arm 24 is fixed on the shaft 18 where the latter projects in past the plate 10 toward the point-rail 2, preferably by a round key 25 and a pin 26 through the hub of the arm and the shaft. The hub spaces the arm 24 out to the middle of the space between the rails, and the guard element 19 is projected down about midway of its length, having a recess thereat receiving the free end part of the arm 24 between the lateral sides of the recess, through which a pin 27 passes transversely and is embraced by the free end part of this arm. The radius of this arm 24 is such that when the element 19 has its top about even with the rail tops as before described, the arm 24 inclines over in the direction of rail convergence, or to the right as shown in the drawings. To bear against the upper side of this inclined arm, or left side as here shown, the element 19 has the adjacent end of the recess inclined, forming the bearing surface 28 conforming to this side of the arm 24.

The idler arms 29 and 30 swing loosely on the respective studs 14, and are confined thereon by the stud heads 17, and project

into recesses in the bottom of the element 19, being suitably spaced from the plate 10 by their hubs of lengths to correspond to the difference in width of the space between the rails at their locations. Pins 31 pass through the lateral sides of the recesses and through the received end parts of the arms 29 and 30. These idler arms are of the same radius as the operating arms 24, and their pivoting in the guard-element recesses is at such a height that, although these arms are journaled higher on the rail 1 and plate 10 than the operating arm 24, all the arms incline at the same angle, as described for the arm 24. Also, the left ends of the recesses have inclined bearing surfaces 32 to rest on the upper or left hand sides of these idler arms 29 and 30 in this position of the parts.

This is the position required of the guard element 19 when the switch is thrown for main-line travel, with the point-rail 2 against the siding or continuous rail 1. When the switch is opened for entrance to the siding or turn-out, moving the point-rail 2 away from the rail 1, and the flanges of the train wheels must pass along the rail 1, the guard element 19 is lowered to a position where its top will not be engaged by the flanges, to avoid injury to the guard element. This is accomplished by a partial rotation of the shaft 18 over to the left, or in direction of rail divergence, first raising the element 19 somewhat above the rails 1 and 2 and then carrying it down to the required lower position as indicated by the dotted lines in Fig. 4. To afford a positive stop and support for the element in this lowered position, wherein, as shown, the arms 24, 29 and 30 are down almost to a horizontal position, the bottom of the element 19 has a recess 33 curved to fit onto the now upturned side of the hub of the arm 24, and similar recesses 34 to fit onto the hubs of the idler arms 29 and 30. The connection of the operating arm 24 to the element 19 is far enough below the top of the element to leave ample thickness or depth of the element at its recess 33; but the connections of the arms 29 and 30 being higher in the element, the hubs of the arms 29 and 30 have recesses 35 admitting the flanges 36 left at opposite lateral sides of the guard-element recesses 34 next to the arm connections therein. These hubs preferably are enlarged on their sides opposite these recesses, as shown, to compensate for the weakening caused by the recesses, as at 37. Between the parts having the arm-receiving recesses, the bottom of the guard element 19 is recessed to give it an inverted channel cross-section, with side flanges 38, so that the element is light, yet amply strong for resisting guarding and operating strains. So that it may be used either for a right-hand turn-out, as here shown, or for a left-hand turn-out, the guard element 19 is made

symmetrical in a transverse sense; the recesses 33 and 34 being continued entirely across the bottom, to rest on the respective arm hubs whether the hubs project to the 5 one side or the other of the element.

The device is so located along the rails 1 and 2 that the shaft 18, at its middle, lies about along the middle of one of the ties 8. This avoids weakening of the siding rail 1 10 between two ties, and permits the shaft 18 to have an outer support in a bearing-block 39 spiked or screwed to the top of the tie 8 near its end, with the shaft 18 extending past this block 39 and receiving a crank 40 15 keyed thereon by a screw 41 and swinging down along the end of the tie 8 with a fork 42 straddling the crank arm and pivoted thereto by a pin transversely through the arm and the fork members. This crank 40 is 20 so positioned on the shaft that it swings about equally past a vertical line in rotating the shaft 18 the required amount for raising or lowering the element 19 as before described. A rod 43, which may be tubular, 25 for lightness and strength, is fixed in the fork 42 and extends therefrom along the ends of intervening ties 8 and over the top of the nearer long tie or head-block 6 that supports the switch-stand as before described. A bell-crank with two arms 44 and 45 is fulcrumed in a bracket 46 spiked or screwed to the top of the tie 6 to swing horizontally; the arms being about 90° apart in their connections, respectively, to the rod 30 43 by a fork 47 similar to the fork 42 at its opposite end, and to a fork 48 that is offset downwardly and connected to one end of a rod 49 similar to the rod 43 but extending transversely of the track inwardly under 35 the rails 1 and 2, where it has a fork 50 at its opposite end straddling and pivoted to a bracket 51 riveted or bolted to the main brace-rod 3. The radii of the bell-crank arms 44 and 45 and of the crank 40 are such, 40 with relation to the radius common to the arms 24, 29 and 30 of the guard-element 19, that the latter is moved completely from one position to the other by throwing the switch one way or the other; and are so positioned 45 that the element 19 is lowered when the siding is opened, and raised when the siding is closed, for main-line travel. The bearings of the arms 24, 29 and 30 are loose enough 50 to make the slight angularity of the siding-rail 1 to the center-line of the guard-element 19 negligible, either for right or left-hand turn-out use; and similarly, the bearings at 55 the crank 40 and the bell-crank arm 44, for the connections of the rod 43, are loose enough to make negligible the effect of the 60 two cranks turning in different planes. Ample clearance is left between all the parts, so that the installation is very simple, yet 65 effective for closing that part of the space between the diverging rails which is liable

to receive and hold such dragging objects as before mentioned.

It will be apparent that the element can be made longer, to extend farther toward the meeting of the rails 1 and 2, thus excluding even smaller dragged objects, or to extend farther in the opposite direction, thus excluding larger objects, or may be extended farther in both these directions, with both results. Or it may be shorter than 75 here shown; and may have more or fewer supporting or idler arms such as the arms 29 and 30, according to its length or the degree of stability desired for its support. Instead of the indirect connection of the device 80 to the switch-stand as here indicated, the connection may be made directly to a part of the switch-stand crank, as will be readily understood by those familiar with the art; or it may be directly connected to the point-rail 2, either near the point thereof, or close to the guard location, with the operative connection proportioned to afford the right degree of up and down guard movement 85 from the varying point-rail degree of movement at various points therealong. The manual switch-operation of the guard up and down is preferred to a yielding mounting for the guard, to be overcome by the pressure of the wheel flanges, as less liable 90 to derangement. Also, the use of the guard between the outside turn-out rail and adjacent point-rail is far more important than such a use between the opposite continuous main-line rail and the turn-out point-rail, 95 which is open for main line use and not liable to catch endangering objects. However, it will be seen that my invention is adaptable to these modified operations and uses, as well as other modifications in structure, proportions, operations and uses in 100 connection with prevention of accidents such as described. Therefore, while certain constructional details are deemed preferable in connection with my invention, and I have 105 shown and described these rather specifically in elucidating the construction and use of my invention, as is required, I do not wish to be understood as being limited to such precise showing and description, but

Having thus fully described my invention, what I claim as new and desire to secure by Letters Patent is:

1. A guard element, means for mounting said guard element between diverging rails 120 of a switch, and a roller at one end of said guard element.

2. An elongated tapered guard element to occupy the space between diverging rails of a switch, and means to movably but positively hold said element with its top substantially in the plane of the tops of said rails.

3. An elongated tapered guard element to occupy the space between diverging rails of 130

- a switch, and means to hold said element with its top substantially in the plane of the tops of said rails or to move said element a substantial distance below said rail tops.
- 5 4. An elongated tapered guard element to occupy the space between diverging rails of a switch, and means to hold said element with its top substantially in the plane of the tops of said rails or to swing said element in 10 direction of rail divergence a substantial distance below said rail tops.
5. An elongated tapered guard element to occupy the space between diverging rails of a switch, and a roller at the wider end of said 15 guard element.
6. A guard element to occupy the space between diverging rails of a switch, and a roller at one end of said guard element, having a crowned periphery.
- 20 7. A guard element to occupy the space between diverging rails of a switch, and having one end constructed to fend objects sideways or upward.
8. A guard element, and a plurality of 25 swinging arms connected to said element for movably mounting said guard element between diverging rails of a switch.
9. A guard element to occupy the space between diverging rails of a switch, a swinging 30 arm connected to said element, and a shaft connected to said arm for swinging said arm.
10. A guard element, and means for mounting said guard element between 35 diverging rails of a switch, to hold said element up in guarding position, or to move said element up and then down in direction of rail divergence to a wheel-flange-escaping position, or up and then down in direction of 40 rail convergence to said guarding position.
11. A guard element, and means for mounting said guard element between diverging rails of a switch, to hold said element in guarding position, or to move said 45 element to a wheel-flange-escaping position and to return said element to said guarding position by a movement of the element from said escaping position past said guarding position and by a continued movement back 50 toward the escaping position.
12. A guard element, and means for movably mounting said guard element on the outside turn-out rail next to the adjacent point-rail of a switch.
- 55 13. A guard element, and means for mounting said guard element on the outside turn-out rail next to the adjacent point-rail of a switch, for movement to a position with its top substantially in the plane of the rail 60 tops or to a position with its top a substantial wheel-flange-escaping distance below said rail tops.
14. A guard element to occupy the space
- between diverging rails of a switch, one of which rails is movable, a swinging arm connected to said element, a shaft connected to said arm for swinging said arm, a crank fixed to said shaft, a rod pivoted to said crank, and means to move said rod for swinging said arm and moving said guard element when said rail is moved.
15. A guard element to occupy the space between diverging rails of a switch, one of which rails is movable, a swinging arm connected to said element, a shaft connected to 75 said arm for swinging said arm, to extend along the top of one of the cross-ties of the switch, toward an end of the tie, a crank fixed on said shaft for swinging along said end of said tie, a rod pivoted to said crank to 80 extend up over another cross-tie of the switch, a bell-crank fulcrumed on this other tie with one arm pivoted to said rod, and another rod pivoted to another arm of said bell-crank and offset downward therefrom 85 for connection below the level of the tops of the ties to a part that moves when said rail is moved.
16. A guard element having a recess in its bottom, and an arm pivoted in said recess 90 to swing said element up or down between two switch rails, said arm swinging over past a vertical position to hold said element in a raised position, and said recess having one side shaped to bear on one side of said 95 arm when said element is in said raised position.
17. A guard element having a recess in its bottom, and an arm pivoted to said element and having a hub, and swinging said element up to guarding position, or swinging said element down from said guarding position with said hub of said arm received in said recess.
18. A guard element having a recess in its 105 bottom with a strengthening flange at one side of said recess, and an arm pivoted to said element and having a hub with a recess in one side, and swinging said element up to guarding position, or swinging said element 110 down from said guarding position with said hub of said arm received in said recess of said element and said flange of said element received in said recess of said hub.
19. A guard element, an operating arm 115 pivoted to said element to swing the element into and out of guarding position, and an idler arm pivoted to said element to maintain said element substantially parallel with a switch-rail top in either position.
20. A guard element, and a plurality of 120 arms pivoted to said element to raise or lower said element, said arms swinging up and then down past a vertical position to bring said element into its final raised position.

FRANK C. ANDERSON.
